APPARATUS FOR EXTINGUISHING FIRES

Wilhelm Tappe, Bucharest, Rumania

Application October 15, 1934, Serial No. 748,288
In Rumania October 17, 1933

7 Claims. (CL 169—25)

This invention relates to a device for extinguishing fires, especially by means of foam, that is to say by means of chemical substances developing a film of bubbles which cover the 5 burning objects and thus suffocate the flames.

An object of the invention is to provide a device by which it is possible to extinguish fires more rapidly and with greater accuracy than heretofore by guiding the extinguishing means, 10 e. g. foam, directly upon the burning objects, thus ensuring the best result with a minimum of extinguishing means.

This device consists of a tube, which can be lengthened to the desired extent by means of 15 some additional tubes screwed one to the other or by a telescopic construction of some tubes, which are so arranged that the one can slide within the other. In both cases this elongated tube being provided with a mouth-piece at the 20 foremost end may be used as a hose for the extinguishing means, or a separate hose for the extinguishing means can be provided within this outer tube or tubes. The tube structure is preferably made of a light but fire-proof material, so that it can be moved through the flames 25 up to the burning objects.

Another object of the invention is the provision of such a tube construction on a wheel base or carriage, on which it is arranged by means 30 of a turntable and an upright jack or frame which itself is arranged on the turntable so that it can be tilted around a horizontal axis, thus rendering it possible to turn the tube into all directions and to give it any desired inclination.

Further objects of the invention and the useful effects attained therewith will be more clearly understood from the description hereinafter in connection with the drawing showing a preferred construction as an example.

Fig. 1 shows a side elevation of a telescopic tube construction on a carriage.

Fig. 2 is a plan view. In both figures the tube is extended to its working position or length.

Fig. 3 shows a front view of the construction partly in section along line III—III in Fig. 2.

Fig. 4 is a longitudinal section along the axis of the tubes. In this figure the tubes are shown in their retracted position so that the one lies 50 within the other. The middle parts of the tubes are omitted.

Heretofore most of the fires are attacked by means of water which is directed from some distance to the burning objects, and in most 55 cases a good result can be attained in this

manner. It is not important that all water-particles reach the burning objects, because the water-quantity is not limited so that even great quantities can be thrown into the flames.

However it is not possible to use water as extinguishing means in all cases, but chemical means are to be used, if e. g. petroleum, gasoline or similar liquids and substances are burning. These chemical means in form of gases or foam are much more expensive than water, 10 and consequently one should try to get the best extinguishing result with a minimum of such expensive substances.

Furthermore it is known that burning tanks of petroleum, gasoline or the like develop a very 15 great heat, so that it is not possible to stay near them. Furthermore there exists also the danger of explosions, so that the firemen are exposed to great danger, if they remain at or go forward to a place from which they could 20 easily guide the streams of extinguishing means to the burning objects or tanks. On the other hand, if they remain at a safe distance from the place of the fire, they are not able with the means known up to now to guide the extinguishing substances so that a good result can be attained with a minimum of these substances.

The instant invention proposes a device with 25 which it is possible to avoid all these drawbacks. 30

The invention proposes to pour the extinguishing means consisting of gases or foam derived from chemical substances directly upon the burning objects, thus getting the useful effect, 35 that the extinguishing means have their greatest efficiency, because they are not attacked or destroyed by the flames, through which they would pass, if they were spread as usually from some distance into the fire.

The principal feature of the invention consists in the proposal not to spirt or throw the extinguishing means into the flames but to directly pour them, even through the flames immediately upon the burning objects.

The means for performing this method is a 40 tube construction, which can be elongated to a certain length, which is made of fire-proof material, so that it can be moved through the flames, and which is arranged on a suitable carrier, so that it may be easily turned into all directions and inclined as necessary. This tube construction serves as a means for guiding the extinguishing means up to the burning objects. The firemen may then stay 15 or 20 meters from the burning objects, and yet have the possibility 45 50 55

of easily bringing the mouth-piece of the tube close to the burning objects.

As shown in the drawing a carriage frame 1, made of angle irons or the like, is supported 5 on four wheels 2. (The right-side wheels are omitted in Fig. 1 to show more clearly the parts lying behind them.)

On the carriage frame a pivot-pin 3 is arranged to support a turntable 4, the outer periphery of which being provided with gear teeth 5. In bearings 6 on the frame 1 a shaft 7 is mounted, which in its middle-part is provided with a worm gear 8, being in mesh with the teeth 5 of the turntable 4, so that the latter may 15 be moved around its pivot 3, if the shaft 7 is turned or rotated by means of a crank 9 or the like.

At the rear side (if in the normal straight position as indicated in the drawing) the turntable 4 carries bearings 10 for arranging a shaft 11 horizontally, which serves as a turning axis for an upright strut or jack 12, which by means of rearwardly extending brackets 13 is connected to this axis. This strut or jack 12 has 25 a frame-like structure as may be clearly seen from Fig. 3, and is so arranged that its center-line in the normal position is parallel to the axis of the pivot-pin 3. In the example shown this center-line lies somewhat in front of the 30 axis of the pivot-pin. Any other suitable construction can also be used.

The shaft 11 carries also a rearwardly extending counterweight 14 which is so formed (Fig. 1) that it can be freely moved over the wheels 35 when the table 4 is turned to the right or the left. At the rearmost end of the counter-weight 14 two cable-drums 15 are arranged on a common shaft 16 which can be rotated by means of a crank 17. The cables 18 which are fastened 40 with one of their ends to the drums 15 are connected with their other ends to the top of the frame-like jack 12, and thus it becomes possible to tilt the jack to any rearwardly inclined position. In connection with the shaft 16 and the 45 crank 17 any known ratchet construction may be provided, so that it will be possible to stop the tilting movement of the jack at any desired point.

Consequently, by means of the crank 9 the 50 table 4 with the jack or strut 12 can be rotated to any position in a horizontal plane, the crank 17 governing the inclination.

A tube 20 is provided and secured with its rear end to the horizontal cross-bar 19 of the 55 frame-like jack 12. Near the front end of this tube 20 a collar 21 is arranged with upright ears 22 at the outer sides, as may be clearly seen from Fig. 3. Connected with these ears 22 stay members or rods 23 are arranged, the other 60 ends of which are fastened to the top of the jack 12, thus creating a rigid-triangular structure. The tube 20 consequently will partake of all movements of the jack 12 in horizontal and perpendicular directions.

65 Telescopically arranged within this first tube 20 two other tubes 24 and 25 are provided which may have nearly the same length as the tube 20, so that the tube construction as illustrated may have a total-length of nearly fifteen meters if, 70 for instance, tube 20 is made five meters long. It is understood that instead of three tubes like 20, 24 and 25 also four or more tubes may be arranged in the same manner thus making a greater total-length if necessary.

75 At the foremost end of tube 25 a mouth piece

26 of any desired form may be applied to which a hose 27 is connected lying within the tubes. This hose 27 can be introduced into the tubes by a hole 28 provided near the rearmost end of the tube 20, so that the hose can easily follow when the tubes are extended. The hose guides the extinguishing means to the mouth-piece from which it can be readily poured upon the burning objects.

Means are provided for extending the 10 telescopically arranged tubes to the desired extent.

To the rearmost ends of the inner tubes 24 and 25 collars 28 and 29 are secured, which serve as means to connect cables 30 and 31 15 thereto. At the front ends of the tubes 20 and 24 rollers 32 and 33 are arranged by means of brackets 34 and 35 and horizontal pins 36 and 37. These rollers 32 and 33 serve as guiding means for the cables 30, 31, the other ends of 20 which are connected to winding drums 38 and 39 respectively, which are supported on horizontally arranged shafts in the frame-like jack or strut 12. By means of cranks (not shown) these shafts and consequently the drums 38 and 25 39 may be rotated so that the cables 30 and 31 are wound. In view of the fact that by winding these cables their length becomes smaller 30 it will be understood that the tubes are moved outwardly up to the desired extent.

To further strengthen the structure two other cable-drums 40 and 41 are arranged within the jack 12 above the drums 38 and 39 and parallel 35 to the same. These drums 40 and 41 can be rotated also by means of cranks to wind cables 42 and 43, the front ends of which are connected to ears 44 and 45 at the sides of collars 46 and 47 fastened to the front ends of the tubes 24 and 25. By spanning these cables 42 and 43 the elongated tube structure will obtain the necessary 40 rigidity.

The device operates as follows:

Assuming that the carriage 1 with the jack 12 and the tube 20 are in the position shown in Figs. 1 and 2, but that the tubes 24 and 25 45 are in their rearmost position as shown in Fig. 4, and that the device is brought near the place of the burning tank of petroleum or gasoline or of any other burning object, then the drums 38 and 39 are rotated at first with the corresponding cranks, so that the tubes 24 and 25 will 50 be moved out of the tube 20, thereby carrying the mouthpiece 26 forwardly as far as possible. The hose 27 connected to the mouth piece will follow.

By rotating the cranks 9 and 17 the tube 55 structure can be rotated and elevated to any desired position so that the mouth-piece comes immediately above the burning objects. By rotating the drums 40 and 41 the cables 42 and 60 43 are spanned so that they hold the tubes in their working position.

Now the valves or cocks can be opened so that the chemical substances forming the extinguishing gas or foam may flow through the hose 27 65 to the mouth-piece 26 and from there directly upon the burning objects.

For retracting the tubes 24 and 25 into the tube 20 it will only be necessary to rotate the drums 38 and 39 in the reverse direction, because the gravity will be sufficient for returning them. The rotation of the cranks 9 and 17 70 in the reverse direction will also bring the jack to its normal position.

The device is particularly advantageous if 75

expensive chemicals are used for producing the extinguishing gases or foam, because it will do with a minimum of such chemicals. If water is used the drawbacks will be lessened which consist especially in the damages created not by the fire itself but by the large quantities of water used for extinguishing purposes and flowing to all sides.

The same good result can be also obtained, if instead of the telescopic structure as described and illustrated several tubes are used, which are screwed one to the other. The details will be nearly the same as those illustrated. Differences exist only in so far as the cables 30, 31 and the corresponding cable drums 38, 39 may be omitted, and as such a tube structure may be used without a separate hose, because the screw-connection will be tight enough for leading the chemicals directly therethrough.

Having now described my invention, what I claim is:

1. An apparatus for extinguishing fires by means of foam forming substances comprising a tube of fireproof material, said tube being adapted to be elongated, a jack adapted to be swung around a horizontal and around a vertical axis, means for elongating said tube and means for staying said tube, the rear end of said tube and said elongating and said staying means mounted on said jack, a mouth-piece at the front end of said tube, an aperture in the side wall of said tube near its rear end, a hose inserted into said tube through said aperture, and being connected with its one end to said mouth-piece within said tube whereby the entire length of the hose from said aperture to said mouth-piece is protected by said tube.

2. An apparatus for extinguishing fires, particularly by means of foam forming substances, comprising a set of coaxial tubes, telescopically extendable, a jack adapted to be swung about a horizontal and about a vertical axis, means for extending said telescopic tubes, means for staying said telescopic tubes, the rear end of the outermost of said tubes and said extending means and said staying means being attached to said jack, a mouth-piece at the front end of the innermost of said tubes, an aperture in said outermost tube near its rear end, and a hose inserted into said tubes through said aperture and being connected with its one end to said mouth-piece within said innermost tube, whereby the entire length of the hose from said aperture to said mouth-piece is protected by said tubes.

3. In an apparatus of the character described, a set of telescopic tubes, a jack member in rigid connection with the rear end of the outermost of said tubes and swingably mounted about a horizontal axis, a stay member attached to the front end of the outermost tube and to the jack member at a distance from the rear end of said outermost tube, flexible stay members attached to the front ends of at least some of the inner telescopic tubes, flexible pull members attached to the rear ends of said inner tubes, each of said pull members being guided at the front end of the tube enclosing the tube to which the pull member is attached, means for pulling said flexible members towards points of said jack member remote from the rear end of said outermost tube, a mouth-piece attached to said innermost tube, and a hose attached to said mouth-piece and extending through all of said tubes.

4. In an apparatus of the character described, a tubular member, a stay member, a structural member, said three members being connected to each other to form a rigid triangle, said triangle being swingable about a horizontal axis near its corner formed by said tubular member and said structural member, said structural member extending upwardly when said tubular member is in its horizontal position, a tubular extension of said tubular member at the latter's end remote from said structural member, a flexible staying means attached to the front end of said tubular extension, means for pulling said staying means towards a point of said structural member, remote from said tubular member, a mouth-piece attached to the front end of said tubular extension, and a hose extending through said tubular member and said tubular extension, and being attached to said mouth-piece.

5. In an apparatus of the character described, a set of telescopic tubes, a stay member, a structural member, the outermost of said telescopic tubes, said stay member and said structural member being connected to each other to form a rigid triangle, said triangle being swingable about a horizontal axis near its corner formed by the rear end of said outermost tube and said structural member, said structural member extending upwardly when said outermost tube is in its horizontal position, flexible staying means attached to the front end of at least one of the inner telescopic tubes, means for extending said telescopic tubes, means for pulling said staying means towards a point of said structural member remote from said outermost tube, a mouth-piece attached to the front end of the innermost telescopic tube, and a hose attached to said mouth-piece, and extending through all said telescopic tubes.

6. In an apparatus of the character described, a set of telescopic tubes including an outermost tube, an innermost tube and at least one intermediate tube, a structural member, a stay member, said outermost tube, said structural member and said stay member being connected to each other to form a rigid triangle, said triangle being swingable about a horizontal axis near its corner formed by said outermost tube and said structural member, said structural member extending upwardly when said outermost tube is in its horizontal position, a first collar and a second collar in rigid connection with said intermediate tube near its rear end and its front end respectively, a flexible member attached to said first collar for extending said intermediate tube, guiding means for said flexible member at the front end of the tube enclosing said intermediate tube, a flexible staying member attached to said second collar, means for pulling said flexible members towards points of said structural member remote from said outermost tube, a mouth-piece attached to the front end of the innermost telescopic tube, and a hose attached to said mouth-piece, and extending through all said telescopic tubes.

7. In an apparatus as claimed in claim 6, a third flexible member for extending the tube enclosed by said intermediate tube, and guiding means for said other flexible member at the second collar of said intermediate tube.
